Term of patent 14 years

(Cl. D33—14)

Fig. 2. Fig. 3.

Fig. 4.

FIGURE 1 is a perspective view of a table embodying our new design;

FIGURE 2 is a fragmentary vertical sectional view along lines 2—2 of FIGURE 1;

FIGURE 3 is a fragmentary enlarged front elevation showing the opposite end from that illustrated in FIGURE 2; and

FIGURE 4 is a sectional view of one of the four identical legs and is taken on the line 4—4 of FIGURE 1.

The side not shown is like the side shown, while the back of the table is conventionally flat.

We claim:

The ornamental design for an end table, as shown and described.
